DOOR CORNER

Robert S. Wisok, Detroit, Mich., assignor to
Wisco, Inc., Detroit, Mich., a corporation of
Michigan

Application June 10, 1950, Serial No. 167,413

5 Claims. (Cl. 189—36)

1

The present invention relates to corner construction for metal doors and has among its objects the provision of a corner construction adaptable for use both at the corners of a door and also at the junction of the side members and cross rails if desired.

Another object of the invention is the provision of a corner structure that will not sag and allow the joint to open and become unsightly.

Another object is the provision of a corner construction that is neat in appearance and in which the securing means is entirely hidden.

Still other objects and advantages will readily occur to those skilled in the art upon reference to the following description and the accompanying drawing in which:

Fig. 1 is a perspective view of a portion of a door showing an upper and a lower corner.

Fig. 2 is a sectional view on line 2—2 of Fig. 6.

Fig. 3 shows a detail, partly in section, of the adjusting means for the bottom of the door.

Fig. 4 is a view in perspective of the securing means.

Fig. 5 is an enlarged view of a detail of the construction.

Fig. 6 is a section on line 6—6 of Fig. 2.

As indicated in the drawings, the door will consist of side members or rails 10 (only one of which is shown) and top and bottom members or rails 11 and 12 respectively. Of these, the side rails 10 and top rail 11 may be identical in cross-section and are of tubular form and are preferably of extruded aluminum or other suitable material.

These members or rails 10 and 11 are generally rectangular and comprise what may be called a body portion 10A having along one of the shorter sides of the rectangle a flange 10B against which will be secured a panel (not shown). Along the opposite short side of the rectangle, the metal will extend outwardly as at 10C to provide a shallow channel.

Upon the inner faces of the short sides of the rectangular body of the members 10, 11 and 12 will be formed low ribs 15 located a short distance from the adjacent long side of the rectangle whereby to provide small grooves or channels and at the base of the flange 10B, inside the latter, is another low rib 16 extending toward and aligned with the metal wall 10D forming the short side of the rectangle adjacent flange 10B.

The only difference between side members 10 and 11 and bottom member 12 lies in the fact

2

that the edge flanges 11C are somewhat longer or higher than the flanges 10C so as to provide a somewhat deeper channel at the bottom of a completed door.

5 In building a door of the members above described, pieces 10, 11 and 12 are cut to suitable length and mitered as indicated at 20. Into the abutting mitered ends of two of such pieces is then inserted the fastening or securing means shown in detail in Figs. 4, 5 and 6.

This securing means consists of a pair of L-shaped right angle members 20 and 21 of resilient material, such as steel, preferably formed as shown; namely, having their edge portions 20A, 21A inclined to the central portion 20B—21B, at a small angle and showing in cross section a shallow, concavo-convex trough or flattened U-shape.

The members 20 and 21 are identical except that one of them, 20, is provided with suitable openings for the passage of screws 22 and is further provided with suitable sheet metal or other nuts 23 adapted to coact with screws 22 and held in position in any suitable fashion on the convex face of the member, as by welding or by means of small tongues 23A struck out of the metal of the member 20.

As stated above, the pair of members 20—21 are inserted in the abutting mitered ends of members 10, 11 and 12 and into the grooves provided by ribs 15 so that the lateral edges of members 20—21 abut the inner surfaces of the rectangular body. When thus positioned the members 20 and 21 are laterally spaced apart and the arm portions thereof are arched away from the adjacent sides of the rails interconnected thereby as perhaps best shown in Fig. 6. The longitudinal edges of each arm portion seat in adjacent corners of the rails. The ribs 15 assist in guiding the members 20 and 21 into the rails, to position the members properly in the rails, and to hold the members against lateral displacement at all times. Also, the ribs 15 hold the members 20 and 21 properly positioned in the rails when the screws 22 are being screwed into the members 20 during assembly of the frame.

Through suitable openings, later closed by plugs 25, the screws 22 in member 20 are screwed down against the face of member 21 to force the central portion of the bowed members apart and thereby exert considerable pressure against the inside walls of members 10, 11 and 12 to maintain the latter against relative movement. From the above it will be apparent that the screws 22 flex the members 20 and 21 toward the adja-

3

cent sides of the rails 10 and 11. When tightened, the screws 22 physically urge members 20 and 21 apart; and by forcing the members 20 and 21 apart, the screws press the arm portions of the members laterally against the sides of the rails to hold the latter assembled. However, by reason of the resilient nature of the members 20 and 21, tightening of the screws 22 also flexes the members and thereby creates internal stresses therein which expand the same transversely and force the longitudinal edges thereof against the upper and lower sides of the rails. This action created by inherent resiliency in the members 20 and 21 supplements the lateral forces exerted by the screws, and the combined action results in an exceedingly effective holding force. It will be observed that the resultant forces tend to "crowd" the longitudinal edges of members 23 and 24 into the internal corners of the rails and that holding forces are exerted laterally and transversely with regard to the members 20 and 21 against the corner surfaces of the rails. The total effect is an improved and exceedingly strong corner construction. Also and perhaps equally important is the fact that the exceedingly strong holding force is obtained by the use of small, lightweight means. If the proper strength and resiliency is present, the members 20 and 21 can be made from relatively light gage metal, thus maintaining the weight of the construction at a minimum and reducing manufacturing costs. All of these factors are important in apparatus of the character here under consideration.

As a further means for insuring against relative movement of the members 20-21 and the members 10, 11, 12, the former may be provided with a plurality of short sharp barbs 35 along their outer edges. These are conveniently formed by notching and forcing one edge of the notch outwardly as shown.

As stated above, the bottom rail 12 is provided with a somewhat deeper edge channel than are members 10 and 11. This is to provide for the reception of an adjusting strip 36 which consists of a channel of suitable dimensions lying within the channel of member 12 and held in proper location by means of an angle member or bracket 31 fixed to strip 36 and extending up into the edge channel of the door side rail 11 where it may be secured by means of a suitable screw 31A passing through a slot 31B in the bracket.

Suitable means for fixing the bracket 31 to strip 36 is shown in Fig. 3 as straps 30A punched up from the metal of strip 36 and receiving the lower end of the bracket.

I claim:

1. A corner construction for fabricated metal structures comprising right-angularly disposed hollow rails having mitered ends abutting together, each rail being provided with generally right-angularly disposed diametrically opposed internal corners, and a pair of relatively thin L-shaped members of resilient material connecting said rails and arranged in laterally spaced relation with the arm portions thereof extending into the hollow interiors of the rails, each of said arm portions being arched transversely and away from the adjacent side of the rail in which it is disposed and the longitudinal edges of each arm portion seating in adjacent internal corners of the rails, and holding means engaging the arched portions of the arms flexing the same toward the adjacent sides of the rails and thereby compressing said arm portions to jam the edges thereof outwardly into pressed frictional engagement

4

with their respective corner surfaces, whereby the holding effect of said holding means is supplemented by stressing of said resilient arm portions.

5 2. A corner construction for fabricated metal structures comprising hollow rails disposed in abutting relation, a pair of laterally spaced members in and bridging the butted ends of the rails, and holding means forcing said members apart 10 and toward opposite sides of the rails, said rails having a pair of aligned internal corners at one side thereof seating the longitudinal edges of one member and another pair of spaced internal corners at the other side thereof seating the longitudinal edges of the other member, said members being of relatively thin, flexible, resilient material and being arched transversely away from the adjacent sides of the rails, said separating means flexing the arched portions of the members and thereby stressing the same to expand 20 the longitudinal edges thereof tightly against the corner surfaces engaged thereby, whereby the tensioned spring action of the members supplements the lateral pressure exerted 25 against the rails by said separating means to hold the rails assembled.

3. A corner construction for fabricated metal structures comprising right-angularly disposed hollow rails having mitered ends abutting together, each rail being provided with generally right-angularly disposed diametrically opposed internal corners, and a pair of L-shaped members of resilient material connecting said rails and arranged in laterally spaced relation with the arm portions thereof extending into the hollow interiors of the rails, each of said arm portions being arched transversely and away from the adjacent side of the rail in which it is disposed and the longitudinal edges of each arm portion seating in adjacent internal corners of the rails, one of said members having a screw-threaded opening therein disposed in alignment with an opening in the adjacent side of the rail, and a screw insertible through the opening in the rail in and threadedly engaging said internally threaded hole, said screw bearing endwise against the other of said members, and urging said members apart laterally against the engaged corner surfaces of the rails, said screw simultaneously stressing the arched portions of the arms to force the longitudinal edges thereof in directions transverse thereto and against the opposed corner surfaces of the rails.

4. A corner construction for fabricated metal structures comprising right-angularly disposed hollow rails having mitered ends abutting together, each rail being provided with generally right-angularly disposed diametrically opposed internal corners, and a pair of L-shaped members of resilient material connecting said rails and arranged in laterally spaced relation with the arm portions thereof extending into the hollow interiors of the rails, each of said arm portions being arched transversely and away from the adjacent side of the rail in which it is disposed and the longitudinal edges of each arm portion seating in adjacent internal corners of the rails, the arched portions of one member having an opening therein and the rail receiving said member having an opening disposed in alignment with said first-mentioned opening, a nut fastened to said member over the opening therein, and a screw insertible through the opening in said rail threaded into the nut and bearing endwise against the other of said members, said screw spreading

the members physically apart and pressing the same laterally against their respective corner surfaces and simultaneously stressing the arched portions of the members to press the longitudinal edges thereof in directions transverse to the arm portions and against opposed corner surfaces of the rails, and means normally closing the openings in the rails.

5. A corner construction for fabricated metal structures comprising hollow rails disposed in abutting relation, a pair of laterally spaced members in and bridging the butted ends of the rails, and holding means forcing said members apart and toward opposite sides of the rails, said rails having a pair of aligned internal corners 10 at one side thereof seating the longitudinal edges of one member and another pair of spaced internal corners at the other side thereof seating the longitudinal edges of the other member, said rails also provided with ribs extending into the 15 hollow interiors thereof behind said members and co-operative with the latter to hold the edges 20

thereof seated in their respective corners, said members being of relatively thin, flexible, resili-
ent material and being arched transversely away from the adjacent sides of the rails so that said holding means flexes the arched portions of the members and thereby stresses the same to expand the longitudinal edges thereof tightly against the corner surfaces engaged thereby, whereby the tensioned spring action of the members supplements the lateral pressure exerted against the rails by said members to hold the rails assembled.
